THE ROYAL ACADEMY.

THE ONE HUNDRED AND FIRST EXHIBITION. SECOND NOTICE.

N° 5. Resuming our review of last month, we have, in this, to say little more than confirmation of the judgment before pronounced. Further experience does but confirm the verdict from the first given, that the present exhibition is a great exhibition known within living memory. Likewise, all that has been said of the ample preparations, good taste, and judicious arrangement of the new galleries, receives echo from the thousands who, beyond all previous precedent, have crowded the rooms given over to the pictures. The success, indeed, has surpassed the most sanguine anticipations. On the other hand, it is generally conceded that serious blunders and indiscretions have been committed. We need not repeat that the great and the multitudes of pictures by native artists, the wholesale admission of works, many inferior in merit, by foreign painters, together with the old grannies, have disgraced the Academy. It is not the fault of the Academicians that they have sought the shelter of the Royal Academy for themselves. In another page we pass under review the opposition exhibition, which the ungenerous conduct of the Academy has provoked. No wonder the outcome of the Royal and the other exhibition in the handsome galleries of Piccadilly, some of the worst pictures are by Royal Academicians; we may further add that the best of the first forty, three have usurped space for no less than forty portraits. Under the grievous pressure of this flagrant abuse, it may be well to recall the recommendation of certain Royal Commissions, that we recollect, in the present parliament, reported in the *Times*, that the present rule, each Academician or Associate is entitled to exhibit eight works of Art as of right. In the opinion of many, even of those who possess this privilege, it is doubtful if any artist, however eminent, should be allowed to exhibit so large a number; and besides the advantage that would ensue from leaving more space for the works of other artists, it may be urged that the any artist restricted to a smaller number, would bestow greater care and pains in their preparation. Accordingly, the committee proposed that Royal Academicians and Associates should lower their privilege from eight to four works; and that the Associates should not even exhibit four as a matter of right, but only on the basis of

merit. We need not point out how greatly by the measure suggested, which, indeed, the experience of the present year seems to render urgent and imperative. But it is not our intention to speak in harsh terms of the Academy; for in the presentation of these magnificently calculated and of the excellent and successful exhibition, justice demands that praise should preponderate over blame. It were too much to expect that the Academy should be wholly free from the faultless and the public bodies and private individuals generally. On the whole, the Academy throughout its career, extending into a second century, has done well for the Arts of this country; and now we trust her to do even better, and that its funds will grow by year beginning, and its prestige and power augmented, we have only to hope, as indeed, we ought to believe, that its conduct will be guided by the sense of duty and responsibility. The exhibition, however, has been doomed to pass under review, notwithstanding the errors committed, a good surgery will follow, and the present blunders are no longer to be deferred; for the sake of the commissioners. "We conceive the continuation of the Academy should rest on a wider, and more liberal basis, and that it should be made more useful than it is at present in promoting the arts, and in aiding the development of public taste. We think the Royal Academy should be viewed as a great national institution for the promotion of Art, and that by the rules and duties which it may fix, its character and宗旨 should be distinctly recognised and defined."

GALLERY NO. VL.

This gallery, 40 feet long by 32 feet wide, presents both architecturally and pictorially a pleasing aspect. We have again to repeat that Mr. Sydney Smirke has shown great tact and taste throughout the whole of his arrangement of space, in the choice and adaptation of colour, and in the application of appropriate and pleasing decoration. This gallery, like the *St. George's*, has a *dressoir* aspect. The light is admitted through a small opening, close in modelled detail of *Grat*, five windows prettily, yet soberly, coloured. The doorways are massive and handsome in solid marble, the walls are tinted in rich marble colour, which, in its decorative character, infests the picture, and the decorative injury upon pictures not strong enough to encounter violent treatment. We note with pleasure that provision is made for the safety of pictures by means of glass burners; in short, every means has been taken, even to the supply of ample divans in the centre of the room, to attract the public, and to minister to the general comfort of visitors. The woodwork, which is all of solid wood, has been thrown up into a dado at about two feet six inches above the ground, at which point the hanging begins. We are glad to observe that the artist is enabled to print large as to "the line" pictures of nearly less advantage under present arrangements, which secure to every picture a fairly good position. Upon the hanging, we have but to remark again, that the pictures are maintained as to size, subject, and colour, whereby the general effect is made agreeable without the infliction of palpable injury to individual works. We find an analysis that out of nine-there pictures here hung, twelve are contributed by Academicians, nine by Associates, and that

seventy-two come from outsiders, British or foreign.

THE ART, in the best sense of the word, cannot assuredly be exhibited in the Hospital, so long as it is possible to produce works so grand in conception, noble in treatment, as "Judith" (1852), by A. Etty, "The Virgin of the Magdalene" (1849), by J. E. H. Hottenroth, "St. Jerome" (1871), by F. Leighton, R.A. Mr. Blumire's reading of the character of "Judith" is one of the grandest on record. Other painters have sometimes made the subject almost ridiculous, but Etty, the English Academician, on the contrary, raises the character into the high sphere of heroism: the deliverer of her people is strong in resolve, and yet her tender nature seems to recoil from the curtain stealthily, and casts a fixed, yet reluctant, eye upon her victim, seen by her only: her lip quivers and blanches in fear; her hand is tremulous, the hand and wrist firmly knit, and since the moment that the will has irreversibly resolved, the moon casts a pallid light, and in depth of mystery lies the broad shadow. The painter has thrown his picture into deep shadow, and the picture is a picture of colour in the shade: the execution is bold, sufficient as an index to the thought; the manner is reicrom—grand. In its simplicity. Assuredly there are few nobler achievements in the exhibition, or, indeed, within the whole range of our English school.

Strong, indeed, is the contrast in style no less than in subject between Mr. Etty's "Judith" and Mr. Leighton's "St. Mary Magdalene, on the day of the Crucifixion," at the tomb of our Lord. The artist has never painted a more impressive picture. Deep meaning is here, and there is here a heroic and anguished countenance. The features are wasted through watching and weeping, and the very soul seems broken under bitterness of despair. Thus the contrast is strong, but the picture, with the exception of the painter's handling, is poor, colour thin and meagre; yet, perhaps, this poverty may have a significance and value. It is fitting that a spirit mourning and weeping should be surrounded by the shades of all decoration and outward signs of joy, is the natural instinct of sorrow. The work "boomed" doubly impressive by its unity; an unbroken monotone pervades the picture, and the picture is a picture throughout is solemn and severe. Altogether the picture must be accounted remarkable, and it comes especially in these times almost as an anachronism. The picture, we may say, is an unexpected proof that religion as Art is an impossibility in this our day and generation.

It is generous of Mr. Leighton to present to the world a picture as large and important as "St. Jerome." Yet were we scarcely prepared to find that artist desirous of being identified by position with Titian, in emulation of whom the noted picture was evidently painted. We accept it however, as a pledge that Mr. Leighton has a greatness in him to which adequate expression has not yet been given; that he is ready on the first opportunity to exhibit his picture decorative for a manner large and simple; that he can, when he likes, cast off a colour somewhat crude and poor for the rich harmonies and the deep tones of *Kinstor* and *Veronese*. Not that "St. Jerome" is in colour faultless, or in form above

United States Patent Office.

ISAAC REHN, OF WASHINGTON, DISTRICT OF COLUMBIA, ASSIGNOR TO
HIMSELF AND NORRIS PETERS, OF SAME PLACE.

Letters Patent No. 100,924, dated March 15, 1870.

MODE OF PRODUCING PHOTO-LITHOGRAPHIC TRANSFERS.

The Schedule referred to in these Letters Patent and making part of the same.

I, ISAAC REHN, of the city of Washington, and District of Columbia, having invented a new and improved Mode of Producing Photo-Lithographic Transfers, do set forth the same in the following specification.

The object of my invention is to produce the most perfect photo-lithographic results by the most simple and certain means, and thus extend the application of the art to all such requirements as involve the necessity of linear delineations. To do this I proceed as follows:

Take of water, thirty-two ounces; gelatine, gum-arabic, or other oxidizable organic matter, four ounces; saturated solution of bichromate of potassa, or the equivalent thereof in bichromate of ammonia or chromic acid eight ounces. Dissolve the gelatine, with a gentle heat, in the water, and, after having removed the solution to a darkened room, add the bichromate solution and stir the whole together. It is then ready for use.

With this solution, kept warm, I coat the requisite quantity of paper, with a soft sponge dipped into the solution, and spread the same evenly over one side of the paper or other suitable material, then hang it up to dry; or the paper may be floated on the surface of the solution, or immersed in it, if that mode is preferred; but, in either of the latter two modes, the solution should be diluted one-third, or thereabout.

This paper, when dry, I expose to the sun-light about ten minutes, that the film may be thoroughly oxidized, when it is to be collected and preserved for subsequent use.

The next step, is to coat this paper a second time with the warmed gelatinous solution, by floating it on the surface of the same in a darkened room, allowing it to remain on until it is thoroughly moistened, then hang it up to dry, as before, and it must be kept from the light until further used.

When about to use the sheets as above prepared, I coat them over, in the manner hereinafter described, with a preparation made as follows, viz:

Take of yellow soap, that being the cheapest, and as good for the purpose as any, one ounce; arrow root, starch, or flour, half an ounce; water, one quart; coloring-matter, a sufficient quantity to give the mass a tint which will be visible after it is applied to the paper; saturated solution of bichromate of ammonia, two drams, the bichromate of ammonia being preferred in this case because of its greater solubility in water than the other bichromates, and less water, therefore, introduced into the compound.

Dissolve the soap in a pint of the water by heat, the starch is to be boiled in the remaining pint, then mix the solutions, and evaporate the whole to the consistence of thick lithographic ink. The coloring-matter (blue is preferable, because it does not

sensibly stop the action of the light) may be added any time before the application of the compound to the paper.

When about to apply the coating, proceed to a darkened room, and, on a slab of glass or stone, add and mix thoroughly the solution of bichromate of ammonia with the mass; then, with a roller, proceed to roll up a stone, in the manner of lithographic printing with this compound; lay the prepared paper on the stone, face down, and pass it through the press. On removing the paper it will be found coated with this sensitized transfer compound. Or the following may be substituted for the method last described, viz:

Take of gelatine three ounces; soap, three ounces; water thirty ounces; saturated solution of bichromate of potassa, twelve ounces; coloring-matter, a sufficient quantity.

Dissolve the gelatine in one-half of the water by heat, and the soap in the balance of the water. Mix these two solutions, and, in the darkened room, add the bichromate solution and the coloring-matter. On this solution, kept warm, float the paper as previously prepared until it is moistened, then hang it up to dry.

The paper thus prepared by either described mode is then ready to be placed under a negative, and exposed to the action of the light, the time being, with a negative of moderate strength, about five minutes in the sunlight, or about fifteen minutes in the diffused light of a clear day. When the action of the light has been sufficient, which may be known on examination of the print, the frame is carried to the darkened room, where the print is removed, then immersed in tepid water, which will discharge all the material from the unlighted portions of the paper except the first or oxidized layer, and a clear sharp print corresponding with the negative is obtained, which print, when sufficiently dried, is ready to transfer to the stone, zinc, or other suitable material, without further manipulation.

The object in the oxidation of the first layer on the paper is to secure a smooth immovable basis on which to make the impression, so that the lines may have better and more clearly defined edges.

The purpose of the second layer is to obtain a soluble layer, susceptible of oxidation by the light, by which also is secured, through the oxidation, the insolubility of those portions on which the light has acted, and a retention thereby of the lines.

I have found in practice that all greasy and unfixed inks, or transferring compounds on prints, however perfect these prints may be when ready for the stone, are more or less mashed in the act of transferring them to the stone, by which the lines are thickened, broken, and the work choked up, rendering the results comparatively imperfect. I have sought to avoid this by

preparing and employing a transfer compound sensitive to the action of light, by which this transfer material may also be oxidized, and thus solidified and fixed.

In the employment of the organic mordant in combination with the oxidizing agent and the transferring substance, I have secured a sure means of avoiding the mashing in the act of transfer, and so perfectly is this obtained by my process that no amount of pressure I have been able to bring to bear on these transfers by the lithographic press, not even when passed through several times in succession, shows any signs of the spreading of the lines, while the transfer thus made readily receives the ink, and all the qualities necessary for printing are secured. The purpose of this third layer will, therefore, be evident.

The object in the introduction of the coloring-matter to the transfer compound is to enable the operator to see distinctly the progress of the discharge of the

transfer compound from the unlighted portions of the print, and that he may thus know when it is complete.

Having described my invention,
What I claim is—

1. The successive application to the paper in a darkened room of a gelatinous oxidizing compound and a transparent or translucent oxidizable transfer compound, substantially as described.

2. The employment of a paper for the production of photo-lithographic transfers, containing the materials for oxidation and transfer prior to the same being exposed to the action of light through a negative, as described.

ISAAC REHN.
